(57) **CLAIM**

We claim the ornamental design for a room scheduling device, as shown and described.

DESCRIPTION

FIG. 1 is a front perspective view of a room scheduling device, according to one embodiment;

FIG. 2 is a rear perspective view of the room scheduling device thereof;

FIG. 3 is a front view of the room scheduling device thereof;

FIG. 4 is a rear view of the room scheduling device thereof;

FIG. 5 is a left side view of the room scheduling device thereof;

FIG. 6 is a right side view of the room scheduling device thereof;

FIG. 7 is a top view of the room scheduling device thereof; and,

FIG. 8 is a bottom view of the room scheduling device thereof.

The broken lines are for purposes of illustrating boundaries and form no part of the claimed ornamental design.

1 Claim, 6 Drawing Sheets
